(57) **CLAIM**

The ornamental design for an elevated binder bin, as shown and described.

DESCRIPTION

FIG. 1 is a top perspective view of an elevated binder bin showing our design;

FIG. 2 is a rear perspective view of FIG. 1;

FIG. 3 is a front view of FIG. 1;

FIG. 4 is an end view of FIG. 1, the opposite end view being a mirror image thereof;

FIG. 5 is a rear view of FIG. 1;

FIG. 6 is a top view of FIG. 1; and,

FIG. 7 is a bottom view of FIG. 1.

The broken lines shown are for illustrative purposes only and form no part of the claimed design.

1 Claim, 3 Drawing Sheets

FIG. 3

FIG. 4

FIG. 5
